(57) CLAIM

We claim the ornamental design for a sole plate of a golf club head, as shown and described.

DESCRIPTION

FIG. 1 is a bottom view of a golf club head including a sole plate.

FIG. 2 is a rear, bottom perspective view of the golf club head of FIG. 1.
